UNITED STATES PATENT OFFICE

JOHN H. LITTLE, OF HIGHLAND PARK, AND JOHN H. HUNT, OF DETROIT, MICHIGAN,
ASSIGNORS TO GENERAL MOTORS RESEARCH CORPORATION, OF DETROIT, MICHIGAN, A CORPORATION OF DELAWARE

REFLECTOR

Application filed September 3, 1927. Serial No. 217,388.

This invention relates to reflectors and more particularly those for use in a headlight of the type ordinarily used on an automotive vehicle.

The broad problem involved in constructing a satisfactory headlight is that of providing a light which will adequately illuminate the roadway nearby and for a considerable distance ahead, but will not appear glaring to the driver of an approaching car, and will illuminate the immediate foreground to a desirable extent. To conform to these requirements, the uppermost rays of the beam should be substantially parallel with the surface of the road and the beam spread sufficient to illuminate the road at the desired distance ahead of the car. Owing to the fact that the car is moving over a more or less rough road and that cars may have the load on the front and rear springs apportioned differently, it has up to the present proved impossible to design a reflector which, when used with a single filament bulb, will produce a beam which adequately illuminates the roadway and does not at any time appear glaring to the driver of an approaching car.

It was as a partial solution to this problem that the two filament headlight bulb was evolved. This type of bulb has two independently energizable spaced filaments. The surface of the reflector is so shaped and the two filaments are so arranged and spaced that when one filament is energized, the beam will be high enough so that the roadway will be illuminated a considerable distance ahead for rapid travel while a shift to the other filament upon the approach of another car will drop the light pattern some distance while maintaining its general shape.

The two filament bulb has been used with two kinds of reflectors, the plain and the fluted reflector. The plain reflector used is usually of a substantially paraboloidal, ellipsoidal or hyperboloidal configuration or a modification of one of these surfaces of revolution. In order to secure the desired lateral dispersion of the beam from a plain reflector, it is necessary to use a lens with vertical corrugations. The fluted reflector renders a vertically corrugated lens unnecessary, a plain

lens being sufficient. The fluted type of reflector comprises segments of surfaces of revolution placed side by side.

In any of the two filament headlights, the upper and lower portions of the reflector adjacent and ahead of the parameter produce a beam which is very little affected by a change from one filament to another. As the upper line of the light pattern must be moved by a change from one filament to another, these portions of the reflector are bent downward about two degrees so that they always reflect into the lower part of the light pattern.

In the normal operation of either the plain or the fluted reflector with the double filament bulb, the filament which gives the high light pattern is used for fast driving. When another car is approaching, the operator shifts to the other filament and lowers the beam until the other car is past, then shifts back to the first filament.

In order to make the most effective use of the light available, that portion of the beam extending a considerable distance ahead of the car should be concentrated on the road, and the pattern should be slightly higher in the center than on the sides while sufficient light should always be directed to the sides and intervening foreground to avoid any extreme differences in intensity over the entire field of illumination. With such a distribution of light the eye of the driver does not need to dilate and contract the pupil to have proper vision for different places or distances within the illuminated area.

With this situation in mind, it is an object of the present invention to provide a reflector for use with a two filament bulb which will vary the normal figure of the usual light pattern by reflecting a small portion of the light to one side of the pattern or above the usual cut off. It is a further object of the invention to provide a reflector for use with a two filament bulb which provides a light pattern of the desired shape, intensity and position, which will not appear glaring to the driver of an approaching car, and in which a change from the raised beam to the lowered beam is instantly obvious to the oncoming driver.

Other objects of the invention will appear

in the course of the following description, taken in connection with the accompanying drawings and appended claims.

In the drawings:

5 Figure 1 is a front view of a plain parabolic reflector embodying our invention, the lower portion being cut away.

10 Figures 2 and 4 are vertical longitudinal sections of the reflector, illustrating diagrammatically the direction of the light rays when the lower and upper filaments respectively are energized.

15 Figures 3 and 5 illustrate the shape and location of the main light pattern secured by use of the lower and upper filaments respectively.

Figures 6 and 7 are vertical longitudinal sections of a modified form of reflector.

20 Figure 8 is a front view of a fluted reflector embodying our invention.

25 Figures 9 and 10 are vertical longitudinal sections of a fluted reflector embodying our invention.

30 Referring to Figures 1, 2 and 4 of the drawings, the numeral 10 indicates a plain substantially parabolic reflector having mounted in the center thereof the light bulb 12 carrying upper and lower separately energizable filaments. In order to secure the desired lateral dispersion of the light rays we provide 35 a suitably designed lens 14. At points adjacent the light bulb we provide the modified reflecting areas 16. These small areas are modifications or variations in the normal contour of the reflector. One embodiment of our invention consists in giving the reflector the appearance of having been bumped in with a 40 tool from the rear side. Owing to the fact that the distance from the filament to the inner surface of the reflector is very short 45 compared to the distance from the reflector to the object illuminated, and that the angle of incidence equals the angle of reflection, it is apparent that a slight modification of the normal contour of the reflector has a marked effect on the direction in which the light is reflected from that point. For illustrative purposes we have magnified the modified parts of the reflector.

50 Referring to Figures 2 and 4, the plain lines indicate the direction of the light rays from the regular sections of the reflector. The dotted lines indicate the direction of the light rays from the modified portions. The upper portions of the modified areas reflect the light slightly upward so that they strike the portion 18 in the light pattern, it being understood that the upper limit of the light pattern has heretofore been a substantially 55 straight line. When the upper filament is energized, the light rays change to a very slightly downward inclination. It must, of course, be obvious that while the filament is theoretically a point, it actually has dimensions. In view of this and the fact that the

modified areas must necessarily have a somewhat curved surface, it is impossible to indicate with any accuracy the direction in which light is reflected from each minute unit of area on the reflector. It is sufficient to state that with the lower filament energized as in Figure 2, the greater part of the light striking the upper half of the modified area will be reflected slightly upward above the main body of the pattern and that when the upper filament is energized, the greater part of this upwardly reflected light is reflected downward. The numeral 20 indicates that part of the upper and lower portions (the latter not shown) of the reflector ahead of the parameter which are inclined slightly downward. The modified areas may be in any part of the reflector except these. As there may be any reasonable number of these modified areas from one up and as they may be at any angle and at any place on the reflector except the portions 20, it is obvious that part of the light may be reflected to increase the intensity in any part of the pattern or to one side of or above or below the pattern.

55 The rays striking the lower portion of the modified areas from either filament are reflected downward and merge with the less intense lower portion of the pattern.

60 In Figures 6 and 7 we have illustrated a modified form of our invention in which the reflector is bent outward instead of inward. The effect is the same as in the preceding views except that now it is the lower half of the modified area 16' that reflects the rays upward above the main body of the pattern and it is the upper half which reflects the rays into the less intense lower portion of the pattern.

65 In Figures 8, 9 and 10, we have illustrated our invention applied to a fluted reflector which is used with a plain lens. Since the surface is fluted, the shape of the modified area may be slightly different from the shape of the modification in a plain parabolic reflector but its operation will be exactly the same.

70 The effect of a small portion of the light thus reflected is greater than will be at first realized. A beam of considerable intensity is required to light the roadway a considerable distance ahead of the car as the light rays strike the surface of the road at a very acute angle. An object above the surface of the road, however, such as a pedestrian or an obstacle in or to one side of the road, is illuminated by rays striking it directly, and a beam of comparatively small intensity is sufficient to render it readily visible.

75 We have thus provided a reflector which may be used to deflect a desired portion of the light to any desired part of or to any side of the usual light pattern. One or more modified areas may be used to reflect light upward or to one side only of the car.

80 The effect of our reflector on the approach-

ing motorist is striking. When the beam from the lower filament is used, the top portion of the beam is ordinarily a short distance below the eyes of the approaching driver. The modified areas reflect a small portion of the light directly into the eyes of the approaching driver. This reflected portion is quite noticeable but so little of the light is thus reflected that no noticeable glare is produced. In fact one's vision remains unimpaired while gazing at such a light from such a position. When the upper filament is energized the light pattern is reflected downward as described and the light from the modified areas no longer strikes the eyes of the approaching driver. The change from the lower to the upper filament is quite marked and is instantly obvious to the driver of the approaching car. By the use of our invention, the advantages of the best reflectors are retained while the light pattern may be varied at will to suit the anticipated uses and requirements of such a headlight.

We claim:

1. A reflector having a central zone lying rearward of its focal plane and an outer zone lying forward of the focal plane, said central zone being formed to project a main beam of light from its focus substantially straight ahead and said central zone being provided with a plurality of light diffusing means of relatively small area for projecting light of low intensity above the top of the main beam, the outer zone being free from said diffusing means.

2. A reflector having a zone lying rearward of its focal plane and constructed to project light emanating from the focus of the reflector in the form of a forwardly directed main beam, said zone being provided with light reflecting means of relatively small area for projecting light emanating from said focus above said main beam; and said means being configurated so that light projected therefrom, when emanating from a source slightly above the focus of the reflector, will be directed below the top position of said main beam emanating from the focus of the reflector.

In testimony whereof I affix my signature.
JOHN H. LITTLE.
